UNITED STATES PATENT OFFICE.

JOSEPH FLATHER, OF NASHUA, NEW HAMPSHIRE.

DESIGN FOR A BOX-LEG FOR LATHES.

SPECIFICATION forming part of Design No. 21,126, dated October 20, 1891.

Application filed July 27, 1891. Serial No. 400,887. Term of patent 14 years.

To all whom it may concern:

Be it known that I, JOSEPH FLATHER, of Nashua, in the county of Hillsborough and State of New Hampshire, have invented a certain new and useful Design for a Box-Leg for Lathes or Planers, of which the following is a specification.

The leading feature of my design consists in the four flanged feet $ffff$ at the corners of the box-leg b . Said feet are substitutes for the usual flange extending continuously around the base of the leg b , the openings at $a a' a'' a'''$ showing the breaks in the continuity of the flange, which has heretofore been formed on the base of the leg. By thus interrupting the continuity of the base of the leg and converting said flange into a series of sections constituting feet at the corners of the leg I make the general contour of said base more pleasing to the eye.

Another feature of my design is the form

given to the brackets B B , which are formed on the leg, at one end thereof, and constitute extensions of the supporting-surface of the leg, the outer sides of said brackets being flush with the sides of the legs, while their edges are curved from b to b' , as shown in the drawing, the curvature of the edges of said brackets giving the leg a graceful appearance and depriving it of the air of stiffness usually possessed by legs of this character.

I claim—

The design for a box leg or stand, substantially as herein shown and described.

In testimony whereof I have signed my name to this specification, in the presence of two subscribing witnesses, this 15th day of May, A. D. 1891.

JOSEPH FLATHER.
